UNITED STATES PATENT OFFICE.

JOHN G. MACCUNE, OF MINNEAPOLIS, MINNESOTA.

COMBINATION BRUSH AND COMB CLEANER AND HOLDER.

Application filed June 5, 1924. Serial No. 718,048.

To all whom it may concern:

Be it known that I, JOHN G. MACCUNE, a citizen of the United States, residing at Minneapolis, in the county of Hennepin and 5 State of Minnesota, have invented certain new and useful Improvements in Combination Brush and Comb Cleaners and Holders, of which the following is a specification.

My invention relates to combination brush 10 and comb cleaners and holders. An object is to provide a device by means of which a brush and comb may be readily cleaned whenever desired and which will serve to hold the brush and comb when they are not 15 being used. Another object is to provide a comb cleaner having a plurality of comb-cleaning elements which are held in such manner as to be maintained under tension. This application is a continuation in part 20 of my prior application Serial Number 469,100, filed May 13, 1921.

The full objects and advantages of my invention will appear in connection with the detailed description thereof and the novel 25 features embodied in my inventive idea will be particularly pointed out in the claims.

In the accompanying drawings, which illustrate the application of my invention,—

30 Fig. 1 is a front elevational view of the device, showing a brush and comb supported thereby. Fig. 2 is a view partly in side elevation and partly in section. Fig. 3 is a side elevational view. Fig. 4 is a view of 35 one of the cleaning wires. Fig. 5 is a fragmentary view showing the manner in which the ends of the wires are attached to the device.

As shown in the drawings, I provide a 40 plate 10 of comparatively thin sheet material, such as metal, having its two end portions 12 and 14 bent into substantially parallel relation. A plurality of comb-cleaning wires 16 extend between said end portions, being attached thereto in any suitable manner. It will be understood that the term wires refers to the comb-cleaning elements regardless of whether or not they consist of a continuous number strung back 45 and forth. It is desirable that the comb-cleaning elements be rough rather than smooth and in the preferred embodiment as shown these elements consist of separate parts each of which is produced by twisting 50 together two strands of wire so as to form eyes 18 at the ends of the elements as best

shown in Fig. 4. When the comb-cleaning elements are attached to the end portions 12 and 14 these portions are pressed toward each other so that when they are released 60 the cleaning elements attached thereto will be put under tension by the spring of the sheet material normally tending to separate said end portions a greater distance from each other. The eyes 18 are shown attached to lugs 20 struck out from the end portions 12 and 14 near the outer margins thereof. After the eyes 18 have been attached to the lugs 20 these lugs may be pressed down so as to firmly anchor the ends of the 65 comb-cleaning elements. In the form shown in Fig. 3 each of the end portions has two rows of lugs 20 struck out therefrom in staggered relation, this arrangement permitting the cleaning elements to be placed close together without unduly weakening the end portions 12 and 14. The plate 10 is provided with a rearwardly offset member 22 whereby a ledge 24 for supporting a comb C is produced and the member 22 is provided 70 with a perforation 26 whereby the device may be suspended. One edge of the plate 10 projects out beyond the wires 16 and is provided with a series of brush-cleaning 75 teeth 28 which extend out in opposite direction from that in which the member 22 extends. Positioned above and forwardly of the ledge 24, and adjacent the ends thereof, are a pair of spaced shoulders 30 and 32 which constitute means for supporting a brush B 80 by its handle.

The operation and advantages of my invention will be readily understood in connection with the foregoing description. The device may be suspended from a wall or 85 other suitable supports by means of the perforation 26 in a well-known manner. When thus suspended the brush and comb will be held in the manner previously stated so as to be convenient for use. In order to 90 clean the brush the device is removed from its support and the bristles of the brush are drawn over the teeth 28, thereby removing extraneous matter such as hairs. By drawing the teeth of the comb along the wires 16 the comb will be effectively cleaned of 95 matter which collects between the teeth thereof, the cleaning action being greatly facilitated on account of the fact that the wires are rough.

I claim:

1. A device of the class described com-

prising a plate of comparatively thin sheet material having its end portions bent into substantially parallel relation, a plurality of comb-cleaning elements extending between said end portions and put under tension by the spring of the sheet material normally tending to separate said end portions, one edge of said plate projecting out beyond said elements, and a series of brush-cleaning teeth formed in said edge.

2. A device of the class described comprising a plate of comparatively thin sheet material having its end portions bent into substantially parallel relation, each of said end portions having two rows of lugs struck out therefrom in staggered relation, and a plurality of comb-cleaning wires attached to said lugs, said wires extending between said end portions over the edges thereof and being put under tension by the spring of the sheet material normally tending to separate said end portions.

3. A device of the class described comprising a plate of comparatively thin sheet material having its end portions bent into substantially parallel relation, said end portions having lugs struck out therefrom, and a plurality of separate unconnected comb cleaning wires, each of which has eyes at its ends and consists of two strands twisted together for the full length between said eyes, the latter being attached to said lugs in such manner that said separate wires extend between said end portions and are put under tension by the spring of the sheet material normally tending to separate said end portions.

4. A device of the class described comprising a plate of comparatively thin sheet material having its end portions bent into substantially parallel relation, a plurality of comb-cleaning wires extending between said end portions, and a rearwardly offset member carried by said plate whereby a ledge for supporting a comb is formed.

5. A device of the class described comprising a plate of comparatively thin sheet material having its end portions bent into substantially parallel relation, a plurality of comb-cleaning wires extending between said end portions, one edge of said plate projecting out beyond said wires, a series of brush-cleaning teeth formed in said edge, and a pair of spaced shoulders extending forwardly from said plate for supporting a brush by its handle.

6. A device of the class described comprising a plate of comparatively thin sheet material having its end portions bent into substantially parallel relation, a plurality of comb-cleaning wires extending between said end portions, a rearwardly offset member carried by said plate whereby a ledge for supporting a comb is formed, said offset member constituting means whereby the device may be suspended, one edge of said plate projecting out beyond said wires, a series of brush-cleaning teeth formed in said edge, and a pair of spaced shoulders projecting forwardly from said plate for supporting a brush by its handle.

In testimony whereof I hereunto affix my signature.

JOHN G. MACCUNE.
